FOLDING STRUCTURE FOR CONVERSION
FROM A CHAIR TO A COT AND VICE
VERSA

Charles E. Pearman, Littleton, Colo.

Application March 6, 1953, Serial No. 340,800

2 Claims. (Cl. 155—45)

1

This invention relates to a folding structure for conversion from a chair to a cot and vice versa and has for its primary object to support a person either in a sitting or in a reclining position and in various positions between the sitting and reclining positions.

Another object is to facilitate the storage of the structure when it is not in use.

A still further object is to enable the occupant to alter his position while occupying the structure and to lock the structure in the selected position.

The above and other objects may be attained by employing this invention which embodies among its features spaced front legs mounted intermediate their ends to move about a common horizontal axis, spaced rear legs mounted intermediate their ends to move adjacent the front legs about the common axis, a cross bar carried by the front legs and extending therebetween adjacent the ends thereof, cross bars carried by the rear legs and extending therebetween adjacent the upper and lower ends thereof, the cross bars carried by both the front and rear legs lying parallel with the common axis and an articulated structure connected adjacent opposite ends to the cross bars adjacent the lower ends of the legs for holding said legs extended and means carried by the legs for adjustment from a sitting to a reclining position and for supporting an occupant of the structure.

Other features include a foot rest frame carried by the rear legs adjacent the upper ends thereof for movement above the front legs about an axis which lies parallel to the common axis, a back rest frame carried by the front legs adjacent the upper ends thereof for movement above the rear legs about an axis which lies parallel to the common axis, and a sheet of flexible material connected to the frames adjacent the ends thereof remote from the upper ends of the legs for supporting a person on said structure.

Other features include extension arms carried by the foot rest frame and extending longitudinally therefrom beyond the upper ends of the rear legs, arm rests pivotally connected to the extension arms and to the back rest frame intermediate the ends thereof, a toothed quadrant carried by a rear leg adjacent its connection to the foot rest frame and hand actuated means carried by the foot rest frame and engaging the teeth of the quadrant for moving the frames relative to one another from a sitting to a reclining position.

2

Still other features include a second quadrant carried by the foot rest frame adjacent an arm rest, and releasable means carried by the arm rest adjacent the second quadrant for engaging the teeth thereof and locking the foot rest frame and back rest frame against relative movement.

In the drawings:

Figure 1 is a side view of a folding structure embodying the features of this invention, certain portions thereof being shown in section more clearly to illustrate certain details of construction.

Figure 2 is a front view of the structure illustrated in Figure 1.

Figure 3 is a top plan view of the structure illustrated in Figure 1.

Figure 4 is a view similar to Figure 1 showing the parts in different positions.

Figure 5 is a view similar to Figure 1 showing the structure folded preparatory to transportation or storage.

Figure 6 is a fragmentary enlarged view partially in section of the position adjusting means.

Figure 7 is an enlarged fragmentary view of the position locking means.

Referring to the drawings in detail this improved structure comprises a bed portion designated generally 10 and an occupant supporting structure designated generally 12. The bed structure 10 comprises a pair of spaced rear legs 14 and 16 which are connected adjacent their upper and lower ends by transversely extending cross bars 18 and 20 respectively to define a substantially rectangular frame. A similar pair of spaced legs 22 and 24 are connected adjacent their lower ends by a cross bar 26 and adjacent their upper ends by a transversely extending downwardly bowed cross bar 28. The legs 14 and 22, and the legs 16 and 24 are connected together intermediate their ends to rotate about a common horizontal axis at 30 to define the base of bed 10, opposite side legs of which are crossed intermediate their ends. Connected to the cross bar 20 between the legs 14 and 16 for

movement about the axis of said cross bar is a link 32 and a similar link 34 is pivotally connected to the cross bar 26. The ends of the links 32 and 34 remote from those which are coupled to the cross bars 20 and 26 are pivotally coupled, as at 36, to provide a stretcher designated generally 38. A suitable stop 40 is carried by the link 34 and overhangs the adjacent end of the link 32 to prevent downward movement of the links 32 and 34 beyond a substantially horizontal position. Thus the stretcher 38 will serve to

hold the front and rear legs extended as shown in Figure 1 when the structure is in use but by breaking the stretcher 38 about the pivot 36, the front and rear legs may be folded together about the common axis 30 to facilitate the transportation and storage of the structure.

Mounted on the leg 14 adjacent the upper end thereof is a quadrant 42 having an arcuate row of teeth 44 projecting outwardly from the side thereof remote from the leg 14 for a purpose to be more fully hereinafter described.

Pivotedly mounted intermediate its ends on the cross bar 18 adjacent leg 22 is a side bar 46 and pivotedly mounted on the cross bar 18 adjacent the leg 24 is a side bar 48. These side bars are joined adjacent their ends remote from the cross bar 18 by an end bar 50 which extends transversely between the side bars 44 and 48 to define a foot rest frame designated generally 52 which is adapted to move in a vertical arcuate path above the front legs 22 and 24 about the axis of the cross bar 18. Extending through the side bar 46 adjacent the upper end thereof and mounted for rotation about its own axis is a shaft 54 carrying adjacent one end a worm 56 which engages the teeth 44 of the quadrant 42 so that when the shaft is rotated, the foot rest frame 52 will be moved in its arcuate path to a selected position relative to the horizontal. A suitable hand crank 58 is carried by the shaft 54 remote from the worm 56 and is coupled to said shaft so that by turning the hand crank the shaft will be rotated.

Pivotedly connected to the front legs 22 and 24 adjacent the upper ends thereof are side rails 60 and 62 which are connected adjacent their opposite ends by a transversely extending cross bar 64 to define with the cross bar 28 a substantially rectangular back rest frame designated generally 66. A cross member 68 extends between the side rails 60 and 62 adjacent the cross bar 64 and secured to the cross member 68 and to the cross member 50 is a length of flexible material 70 which forms the supporting surface for the occupant of the structure. Pivotedly connected as at 72 to the end of the side bar 46 remote from the cross member 50 is an arm rest 74 which is pivotedly connected, as at 76, to the side rail 60 intermediate the ends thereof. A similar arm rest 78 is pivotedly connected to the side bar 48 adjacent its upper end, as at 80, and is pivotally connected, as at 82, to the side rail 62, intermediate the ends thereof.

Mounted, as at 84, for rocking movement above the arm rest 78 is a latch member 86 carrying a depending tooth 88 which is adapted to engage the teeth of a quadrant 90 which is fixed to the side bar 48 in concentric relation about the pivotal connection 72. A lever arm 92 is carried by the latch member 86 and extends outwardly therefrom in the opposite direction thereto so that movement of the lever arm in a vertical arcuate path about the rockable connection 84 the latch member 86 will be moved into and out of contact with the quadrant 90. A compression coil spring 94 is seated in a recess 96 formed in the arm rest 78 and engages the under side of the lever 92 to urge the lever 86 toward the quadrant 90 and the tooth 88 will move into a notch between the teeth of the quadrant 90 as will be readily understood upon reference to Figure 7.

In use the legs 14 and 16 and 22 and 24 are extended as shown in Figure 1 with the stretcher 38 fully extended to hold the legs spread and to

provide a base 10 for the structure. The user may before or during occupation of the structure adjust the angles of the foot rest frame 52 and the back rest frame 66 by moving the lever 92 against the effort of the spring 94 to disengage the tooth 88 from the quadrant 90 and upon turning the hand crank 58, the foot rest frame will be rotated about the axis of the cross bar 18 and simultaneously the back rest frame 66 will be moved by the arm rests 74 and 78 from either a fully reclining position in which the foot rest frame 52 and back rest frame 66 lie in substantial alignment as illustrated in the broken lines in Figure 4 or into the chair forming position illustrated in Figures 1 and 2. Obviously by the use of this structure the occupant may alter his position from a sitting to a reclining position or return to the sitting position without moving from the supporting sheet 70 by the simple releasing of the tooth 88 from the quadrant 90 and turning the shaft 54 by the hand crank 58.

When it is desired to fold the structure for transportation or storage, the parts are moved to the position illustrated in Figure 5 so that the structure will occupy the minimum amount of space and the stretcher 38 will be broken on the joint 30 to permit the front and back legs to be folded together.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

1. A folding structure for conversion from a chair to a cot and vice versa, said structure comprising spaced front legs mounted intermediate their ends to move about a common horizontal axis, spaced rear legs mounted intermediate their ends to move adjacent the front legs about the common axis, a cross bar carried by the front legs and extending therebetween adjacent the lower ends thereof, cross bars carried by the rear legs and extending therebetween adjacent the upper and lower ends thereof, the cross bars carried by both the front and rear legs lying parallel with the common axis, an articulated stretcher connected adjacent opposite ends to the cross bars adjacent the lower ends of the legs for holding said legs extended, a foot rest frame carried by the rear legs adjacent the upper ends thereof for movement above the front legs about an axis which lies parallel to the common axis, a back rest frame carried by the front legs adjacent the upper ends thereof for movement above the rear legs about an axis which lies parallel to the common axis, extension arms carried by the foot rest frame and extending longitudinally therefrom beyond the upper ends of the rear legs, arm rests pivotally connected to the extension arms and to the back rest frame intermediate the ends thereof, a sheet of flexible material connected to the frames adjacent the ends thereof remote from the upper ends of the legs for supporting a person on said structure, a toothed quadrant carried by a rear leg adjacent its connection to the foot rest frame, and hand actuated means carried by one of the extension arms of the foot rest frame and engaging the teeth of the quadrant for moving the frames relative to one another.

2. A folding structure for conversion from a chair to a cot and vice versa, said structure com-

prising spaced front legs mounted intermediate their ends to move about a common horizontal axis, spaced rear legs mounted intermediate their ends to move adjacent the front legs about the common axis, a cross bar carried by the front legs and extending therebetween adjacent the lower ends thereof, cross bars carried by the rear legs and extending therebetween adjacent the upper and lower ends thereof, the cross bars carried by both the front and rear legs lying parallel with the common axis, an articulated stretcher connected adjacent opposite ends to the cross bars adjacent the lower ends of the legs for holding said legs extended, a foot rest frame carried by the rear legs adjacent the upper ends thereof for movement above the front legs about an axis which lies parallel to the common axis, a back rest frame carried by the front legs adjacent the upper ends thereof for movement above the rear legs about an axis which lies parallel to the common axis, extension arms carried by the foot rest frame and extending longitudinally therefrom beyond the upper ends of the rear legs, arm rests pivotally connected to the extension arms and to the back rest frame intermediate the ends thereof, a sheet of flexible

material connected to the frames adjacent the ends thereof remote from the upper ends of the legs for supporting a person on said structure, a toothed quadrant carried by a rear leg adjacent its connection to the foot rest frame, hand actuated means carried by one of the extension arms of the foot rest frame and engaging the teeth of the quadrant for moving the frames relative to one another, a second quadrant carried by one of the extension arms of the foot rest frame adjacent an arm rest, and releasable means carried by the arm rest adjacent the second quadrant for engaging the teeth thereof and locking the foot rest frame and back rest frame against relative movement.
